SANDING MACHINE

Adolphe Loucony, Bridgeport, and Harry Eick, Milford, Conn., assignors to The E. W. Carpenter Manufacturing Company, Bridgeport, Conn., a corporation of Connecticut

Application June 15, 1946, Serial No. 677,053

8 Claims. (Cl. 51—194)

1

This invention relates to stationary sanding machines.

An object of the invention is to provide an improved stationary sanding machine which has wide application and may be used in finishing various perpendicular and angularly located surfaces of both large and small workpieces.

Another object of the invention is to provide a sanding machine as above, which is extremely simple in construction and economical to manufacture.

Still another object of the invention is to provide a sanding machine of the above type which is convenient to use, and in which the abrading elements of sandpaper, emery cloth and the like may be quickly and easily replaced when worn out.

In accomplishing the above objects there is provided by the invention a machine comprising a base having a rotatably mounted horizontal shaft which extends across the top thereof. A novel sanding element is carried by the shaft within the confines of the base, the said element comprising a rotary drum having simple and improved means for securing to it an encompassing sheet of sandpaper or the like. Cooperable with the drum is a large flat work rest, in the form of a table, which is pivotally mounted on the top of the base, and which has a transverse slot through which the sanding drum extends. By the use of simple and novel means which are provided for manually raising or lowering the table with a micro movement and for locking it in any adjusted position, workpieces which are fed along the table over the sanding drum may be given a very accurate and fine finish.

For finishing surfaces of smaller area, whether these be perpendicular, or angularly located, means are provided at one end of the shaft including a sanding disk and including a novel work rest in the form of a tiltably mounted plate extending across the face of the disk and carrying an angularly adjustable slide or mitre head. The work-rest plate is secured to the base of the machine by a simple pivotal mounting, and has means cooperable with the base for enabling adjustment of the plate, and for locking the latter in various angular positions.

The organization as provided by the invention is such that sanding operations may be performed on a large variety of workpieces having either squared or angularly located surfaces to be finished. Also, certain concave and convex surfaces may be readily finished by use of the ma-

2

chine, the particular sizes suitable for finishing being limited by the diameter of the sanding drum.

Indicia are provided in connection with the work guides to enable the angularity of the surface being finished to be read directly, or to be readily computed.

Other features and advantages will hereinafter appear.

10. In the accompanying drawings:

Figure 1 is a top or plan view of the sanding machine of the invention.

Fig. 2 is a front elevation of the machine, a portion of the work table being broken away and shown in section to reveal the cross-sectional shape.

Fig. 3 is a side view of the machine, partly in elevation and partly in section on the line 3—3 of Fig. 1.

20. Fig. 4 is a vertical section taken on the line 4—4 of Fig. 1, but with the sanding drum rotated so that the clamping means is on top.

Fig. 5 is a fragmentary section of the sanding drum taken on the line 5—5 of Fig. 1.

25. Fig. 6 is a fragmentary section on the line 6—6 of Fig. 5.

Fig. 7 is a side view partly in elevation and partly in section of the table-adjusting mechanism, and

30. Fig. 8 is a section on the line 8—8 of Fig. 7.

Referring to Figs. 1 and 2, the improved stationary sanding machine of this invention comprises an upright base or pedestal 10 which is preferably formed of a metal casting, the base having at its rear portion backwardly projecting lugs or ears 11 carrying a cylindrical pivot bar 12. The bar 12 passes through and supports lugs 13 depending from a large flat work rest or table 14, the latter being thereby mounted for pivotal raising or lowering movement on the base. Axial shifting of the pivot bar is prevented by spring retainer rings 12a, Fig. 1, which are accommodated in annular grooves provided for the purpose.

40. At its top the base 10 rotatably carries a horizontal shaft or spindle 15, the latter being mounted in anti-friction bearings 16 secured in opposite side walls 17 of the base, Figs. 1, 2 and 4, and being driven through a pulley 15a secured on the spindle adjacent one end thereof.

45. In accordance with the invention a novel sanding drum 18 is provided on the spindle 15 between the anti-friction bearings 16 thereof, the said drum projecting upward through a laterally extending slot 19 provided in the table 14.

As shown in Figs. 4 and 5, the drum 18 comprises a cylinder 20 rolled of sheet metal, the adjacent edges 21 of the cylinder being spaced from each other and being joined to flanges 22 of a metal channel strip 23, the latter having side walls 24 and a bottom wall 25 all located within the cylinder. The flanges 22 of the channel strip can be joined to the cylinder edges 21 in any suitable manner, as by riveting, spot welding etc., although the latter method is at present preferred.

By this construction a longitudinal recess 26 is provided in the drum 22, the said recess being defined by the walls 24 and 25 of the channel strip 23. The recess 26 serves to accommodate clamping means for securing in place the edges 27 of a sheet of sandpaper 28 wrapped around the drum 20, the said means comprising an outer clamping strip 29 and an inner channel-shaped clamping strip 30, both strips extending for the full length of the recess 26.

The inner clamping strip 30 has outwardly extending flanges 31 along its edges, provided for the purpose of engaging inwardly offset portions 32 of the flanges 22 of the channel strip 23. By such engagement, the clamping strip 30 is predeterminedly located in the recess 26 in an operative clamping position adapted for securely holding the edges 27 of the sandpaper 28. The outer clamping strip 29 has longitudinally extending shoulders 33 on the inside along the opposite side edges, the said shoulders being cooperable with the flanges 31 of the inner clamping strip to securely grip the edges 27 of the sandpaper and clamp the latter to the cylinder 20.

A novel operation is provided in clamping the edges of the sandpaper 28 by the provision of resilient means engageable with the clamping strips 29 and 30, the said means being in the form of compression springs 34 and 35 located respectively between the strips 30 and 23, and the strips 29 and 30. The springs 34 and 35 are preferably carried on the shanks of clamping screws 36 which pass through the clamping strips 29 and 30 and are countersunk in the outer strips 29. The clamping screws 36 are threaded into square nuts 37 which are located along the bottom wall 25 of the channel strip 23 and are secured against outward movement therefrom by fingers 38 lanced from the side walls 24 of the strip, Figs. 5 and 6.

A plurality of clamping screws 36, and a plurality of springs 34 and 35 may be provided on the drum 18, located both at the ends of the drum as shown in Fig. 4, and intermediate the said ends.

As clearly shown in Fig. 5, the springs 34 are heavier and therefore stronger than the springs 35, and thus the clamping structure operates in a novel manner to enable replacement of the sandpaper 28 to be quickly and conveniently made. In accomplishing such replacement, the clamping screws 36 are fully loosened, each approximately an equal amount. During the initial movement of such loosening, the clamping strips 29 and 30 will remain together and will be moved simultaneously outwardly of the recess to a certain degree.

This action occurs due to the compression springs 34 being heavier and stronger than the springs 35 and therefore expanding prior to expansion of the latter springs. As the loosening of the screws 36 is continued, the springs 34 attain their free length, causing the clamping strips 29 and 30 to be held in an outward position in the recess 26, and the springs 35 then expand and

cause separation of the clamping strips so as to release the edges 27 of the sandpaper. It should be noted that the release of the sandpaper is effected without the screws 36 being entirely removed from the nuts 37, so that the entire clamping assembly is merely loosened and does not come apart.

Upon the sandpaper 28 being released, it may be easily removed from the drum and a fresh 10 piece of sandpaper quickly inserted in the following manner: One edge of the sandpaper is inserted between the clamping strips 29 and 30, the paper wrapped around the cylinder 22, and then the other edge inserted between the clamping 15 strips. While the sandpaper is being held tightly in place around the cylinder with one hand, the screws 36 are tightened equal amounts at a time by a screwdriver held in the other hand. During 20 the initial tightening movement of the screws 36 the springs 35 will be compressed and the clamping strips 29 and 30 brought together. This causes the edges 27 of the new sheet of sandpaper to be gripped with a fairly substantial pressure. It will be noted that, by the provision of a central 25 web 39 extending along the inside of the outer clamping strip 29 the edges 27 of the sandpaper are caused to be folded, thereby causing a better retention of the sandpaper edges during the installation of the paper, and also during operation 30 of the machine.

As the screws 36 are driven further into the drum 18, the strips 29 and 30, which are now together and securely holding the edges 27 of the sandpaper, are forced simultaneously deeper into 35 the recess 26 of the drum, causing a compression of the springs 34. By this action the clamping strips will carry the edges 27 of the sandpaper with them into the drum recess 26 and cause the sandpaper to be tightly pulled and wrapped 40 around the said drum. As the screws 36 are finally tightened the flanges 31 of the inner clamping strip will engage the offset portions 32 of the channel strip 23, and the shoulders 33 of the sandpaper against the flanges 31. A positive gripping of the sandpaper is thus accomplished, so that the latter under no circumstances becomes loose from the drum 18 during use.

50 The sheet metal cylinder 20 is secured to the spindle 15 by end disks 40, Figs. 4 and 5, the said disks having peripheral shoulders 41 for engaging and positioning the cylinder ends. The disks 40 are held against rotation on the spindle 15 by suitable set screws 42 which may be spotted into the spindle to effect a positive lock.

In accordance with the invention the mounting disks 40 are provided with counterweights 43 located diametrically opposite the recess 26 in the drum 18, and by this organization the weight of 60 the clamping means in the recess 26 is compensated for, so that the drum 18 is dynamically balanced.

For the purpose of adjustably raising or lowering 65 the table 14 with respect to the sanding drum 18 the invention provides a simple and novel adjusting and locking mechanism. This mechanism comprises a lug 44 on the front wall 45 of the base 10, the said lug carrying a stud 46 which passes horizontally therethrough and is locked 70 against turning by a shoulder 44a engaging the head 46a of the stud. At its end the stud 46 is threaded to be received in a manually operable clamping nut 47. The stud 46 also carries a compression spring 48, and between the spring 48 and 75 the nut 47 a cam lever 49 is located, having a cam-

ming portion 50 for engagement with an undersurface 51 of the table 14. Between the lug 44 of the base 10 and the cam lever 49 a bifurcated lug 52 extends, the said lug being integral with the table 14 and dependent therefrom.

Referring to Fig. 8 when the manually operable nut 47 is tightened with the lug 52 of the table 14 in the position shown, the side of the lever 49 will clamp the lug 52 and therefore hold the table 14 in adjusted position. When it is desired to raise or lower the table 14, the nut 47 is loosened, whereupon the cam lever 49 may be moved either forward or backward, causing the cam portion 50 thereof to raise or lower the table. After the desired setting is found, tightening of the nut 47 will again clamp the lug 52 of the table and hold the latter securely in the newly adjusted position. It will be noted that, upon loosening of the nut 47, the compression spring 48 serves to separate the lever 49 from the base lug 44, thereby effecting a positive release of the lug 52 of the table.

Under certain circumstances it may be desirable to use the sanding drum 18 without benefit of the table 14, and accordingly the table may be swung upward and backward about the pivot bar 12 after the nut 47 has first been loosened. The table 14 can swing through an angle greater than ninety degrees so that it is held by its weight in the raised, inoperative position. At the time that the table is again lowered, it will be found that the spring 48 holds the cam lever 49 separated from the base lug 44, so that the lug 52 of the table is readily interposed between the base lug and cam lever without interference.

Referring to Fig. 5, when the clamping strips 29 and 30 are forced into the recess 26 of the drum to hold the sandpaper securely in place, the outer surface 53 of the clamping strip 29 is located so as to lie substantially in the cylindrical surface defined by the sandpaper 28, and as shown, this surface 53 is made convex for this purpose.

We have found that, according to the organization as provided above, workpieces may be accurately sanded and finished by resting them on the table 14 and passing them over the rotating sanding disk 18. According to the amount of finishing which has to be done, the table 14 may be raised or lowered minute amounts by the cam lever 49, and the relationship between the top surface of the table and the drum 18 may be accurately determined and held. By having the drum 18 project only slightly above the table 14, and by using fine sandpaper on the drum, very fine and accurate finishing of a workpiece may be accomplished. By applying a coarser sandpaper to the drum 18 and lowering the table 14 to a greater extent, a deeper finishing cut may be taken and the coarser finishing operations readily performed.

Where workpieces have surfaces which cannot be readily finished by use of the sanding drum 18, as for instance surfaces having a precise angular relation with respect to adjacent intersecting surfaces, such finishing may, however, still be accomplished with the machine of this invention. Referring to Figs. 1 and 2, one end of the spindle 15 has mounted thereon an accurately aligned sanding wheel or disk 54 having secured to its outer face a sandpaper disk 55.

Cooperable with the sanding disk 54 is a work rest comprising a flat plate 56 which is tiltably mounted on the base 10 and which carries an angularly adjustable miter head 57 mounted on a slide bar 58.

Simple and economical-to-manufacture means

are provided for tiltably mounting the work rest 56, the said means comprising a lateral extension 59 at one corner of the work rest, carrying a pivot pin 60 which is received in a bracket 61 secured to one side wall 17 of the base. The bracket 61 has a depending arm 62 the lower end 63 of which is extended horizontally and carries a hand screw 64. Cooperable with the screw 64 is a quadrant plate 65 rigidly secured to the work rest 56, the said plate having an arcuate slot 66 through which the screw 64 extends. By tightening the screw 64 the quadrant plate 65 is clamped firmly to the arm 62 so that the work rest 56 is held against movement. Upon the screw 64 being loosened, the work rest 56 may be moved through an arc about the pivot pin 60, and the angularity of the rest may be indicated by indicia 67 on the plate 65.

The hand screw 64 serves a double purpose. It not only clamps the plate 65 to the arm 62 to lock the work rest in adjusted position, but it also prevents the work rest from separating from the base 10, since it prevents relative movement between the extension 59 and bracket 61 axially of the pivot pin 60. The latter may be fixed to either the said extension or the bracket, and will thus be retained in proper position. However, when it is desired to remove the work rest 56 from the base, this may be quickly accomplished by merely first removing the hand screw 64, whereupon the work rest may be shifted forwardly so that it will disengage the pivot pin 60 from either the extension 59 or bracket 61.

By the above construction perpendicular or angular surfaces of workpieces may be quickly and accurately finished by sanding. Desired angles may be obtained through use of the mitre head 57, or by tilting the work rest 56, or by a combination of both, and this organization in conjunction with the sanding drum 18 enables most sanding operations on a workpiece to be performed with ease and accuracy.

Variations and modifications may be made within the scope of this invention and portions of the improvements may be used without others.

We claim:

1. In a sanding machine, a cylindrical drum having a longitudinal recess in its outer surface, extending substantially from end to end and having shoulders in said recess; a pair of cooperable clamping strips securing between them the edges of sandpaper wrapped around the drum, the said strips occupying the drum recess in superposed relation, the clamping strips having a thickness that the surface of the outer strip lies in the cylindrical surface defined by the sandpaper when said shoulders are engaged; yieldable means holding the inner strip in extended position in the recess whereby the said shoulders are separated from each other; and clamping means for forcing the said strips together and forcing said shoulders into engagement with each other, the said yieldable means opposing the clamping means in a manner that the strips are first brought together to seize the sandpaper between them and then moved simultaneously inward whereby the said shoulders engage each other and prevent further inward movement of the strips.

2. In a sanding machine, a cylindrical drum having a longitudinal recess in its outer surface, extending substantially from end to end; a pair of cooperable clamping strips securing between them the edges of sandpaper wrapped around the drum, the said strips occupying the drum

recess and one strip lying outside of the other; and spring means between the strips for separating the same when the sandpaper is being released.

3. In a sanding machine, a cylindrical drum having a longitudinal recess in its outer surface, extending substantially from end to end; a pair of cooperable clamping strips securing between them the edges of sandpaper wrapped around the drum, the said strips occupying the drum recess and one strip lying outside of the other; spring means between the strips for separating the same when the sandpaper is being released; and stronger spring means between the inner clamping strip and the drum for moving the strips outwardly of the recess when the sandpaper is being released.

4. In a sanding machine, a cylindrical sheet-metal drum having adjacent longitudinal edges spaced from each other; a channel strip within the drum, having its edges respectively secured to the longitudinal edges of the drum, the said strip thereby forming a longitudinal recess in the drum surface; threaded nuts carried in the channel strip, the side walls of the latter having lanced fingers overlying the nuts to prevent their being lifted out of the strip; a pair of cooperable clamping strips for securing between them the edges of sandpaper wrapped around the drum, the said strips being located one outside of the other, and extending along the said longitudinal recess, and the inner clamping strip being of channel shape, and receiving a portion of the outer strip; screws passing through the clamping strips and into the said nuts for drawing the strips into the recess of the drum and clamping the edges of the said sandpaper; and spring means between the clamping strips for separating the latter when the screws are loosened.

5. In a sanding machine, a cylindrical sheet-metal drum having adjacent longitudinal edges spaced from each other; a channel strip within the drum, having its edges respectively secured to the longitudinal edges of the drum, the said strip thereby forming a longitudinal recess in the drum surface; threaded nuts carried in the channel strip, the side walls of the latter having lanced fingers overlying the nuts to prevent their being lifted out of the strip; a pair of cooperable clamping strips for securing between them the edges of sandpaper wrapped around the drum, the said strips being located one outside of the other, and extending along the said longitudinal recess, and the inner clamping strip being of channel shape, and receiving a portion of the outer strip; screws passing through the clamping strips and into the said nuts for drawing the strips into the recess of the drum and clamping the edges of the said sandpaper; spring means between the clamping strips for separating the latter when the screws are loosened; and spring means between the inner clamping strip and the channel strip for moving the strips outwardly of the recess upon the screws being loosened.

6. In a sanding machine, a cylindrical sheet-metal drum having adjacent longitudinal edges spaced from each other; a channel strip within the drum, having its edges respectively secured to the longitudinal edges of the drum, the said

strip thereby forming a longitudinal recess in the drum surface; threaded nuts carried in the channel strip, the side walls of the latter having lanced fingers overlying the nuts to prevent their being lifted out of the strip; a pair of cooperable clamping strips for securing between them the edges of sandpaper wrapped around the drum, the said strips being located one outside of the other, and extending along the said longitudinal recess, and the inner clamping strip being of channel shape, and receiving a portion of the outer strip; screws passing through the clamping strips and into the said nuts for drawing the strips into the recess of the drum and clamping the edges of the said sandpaper; spring means between the clamping strips for separating the latter when the screws are loosened; and springs means between the inner clamping strip and the channel strip for moving both strips outwardly of the recess upon the screws being loosened, the last-named spring means being stronger than the first-named spring means and causing the clamping strips to first move simultaneously outward of the recess prior to their becoming separated.

25 7. In a sanding machine, a rotary drum having sandpaper disposed around its surface; a table movably mounted adjacent the drum, for supporting workpieces; and means including a manually operable cam lever, for shifting the table relative to the drum for adjustment purposes and manually operable means acting on the cam lever for locking the lever in different adjusted positions.

30 8. In a sanding machine, a rotary drum having sandpaper disposed around its surface; a table movably mounted adjacent the drum, for supporting workpieces; means for locking the table in any of a number of adjusted positions, the said means including a lug on the table, and 35 including a pair of members engageable with the lug for clamping the latter, one of the said members comprising a manually operable cam for shifting the table relative to the drum for adjustment purposes; and a spring between the 40 clamping members for automatically spreading the latter when the said locking means is released.
